UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

INSOLE AND PROCESS OF MAKING THE SAME.

1,206,927.

Specification of Letters Patent.

Patented Dec. 5, 1916.

Application filed September 23, 1916. Serial No. 121,875.

To all whom it may concern:

Be it known that I, AUGUST R. SCHOENKY, a citizen of the United States, residing at Somerville, county of Middlesex, State of Massachusetts, have invented an Improvement in Insoles and Processes of Making the Same, of which the following description, in connection with the accompanying drawing, is a specification, like characters on the drawing representing like parts.

This invention relates to a composite insole composed of two layers of thin leather or other sheet material.

It has heretofore been proposed to make a composite insole composed of an outer member or layer which has its edge folded over on the body of the material and then bent upwardly therefrom, and an inner layer which has its edge folded upwardly and which is received within the upturned edge of the outer layer. Examples of insoles having this construction are shown in United States Letters Patent to George Coleman, No. 1,062,536, dated May 20, 1913, and to E. H. Taylor, No. 1,145,094, dated July 6, 1915.

The insole of the present invention is of the general type illustrated in the above-mentioned patents and the objects of the invention are to provide a novel insole of this type having an inseam-receiving rib so constructed that it can be readily beaten down in a beating-down machine after the insole has been sewed to the upper and welt, and also to provide a novel method by which this insole can be made.

In making my improved insole, I first make the inner member from a blank of sheet material of the proper size and shape by folding the edge portion of the blank over onto the body thereof. This folded blank is then placed on another blank of sheet material from which the outer member is formed, said two blanks being so positioned relative to each other that the edge portion of the blank for the outer member will project beyond the folded edge of the inner member. The projecting edge of the outer member is then folded back on itself into contact with the periphery of the fold-

ed blank, the peripheral edge of the outer member being shaped to present a lip. In this folding operation of the outer member, the folded inner member has the function of a die or former to assist in giving the proper shape to the outer member.

In order to give a better understanding of my invention, I have illustrated in the drawings a selected embodiment thereof which will now be described, after which the novel features will be pointed out in the appended claims.

Figure 1 of the drawings is a view of the blank from which the inner member is formed; Fig. 2 shows said blank with the edge portion folded over onto the body thereof; Fig. 3 is an enlarged section on the line 3—3, Fig. 2; Fig. 4 shows the blank from which the outer member is formed, said view showing in dotted lines the folded inner member positioned on the outer member; Fig. 5 is a sectional perspective view showing the folded inner member positioned on the outer member before the edge of the outer member is folded; Fig. 6 is a similar view showing the edge of the outer member folded; Fig. 7 is a perspective view of a completed insole made in accordance with my invention.

The inner and outer members of my improved insole are indicated at 1 and 2, respectively, and each of these is made of sheet material which may be either relatively-thin leather or fabric, or any other similar material. The inner member 1 has the edge portion thereof folded back on itself, as shown at 3. The outer member 2 projects beyond the periphery of the inner member 1, the projecting part 4 of said member 2 being formed by folding the material of the member 2 back on itself and then bending the edge upwardly to form the upstanding rib 5.

In making my improved insole, I first form the inner member 1 from a blank shown at 6 in Fig. 1. This blank has the general shape of an insole and is provided near the heel with the inwardly-directed slits 7. The edge portion of the blank 6 from the slit 7 forwardly is then folded over

against the body thereof, as shown in Figs. 2 and 3, the folded-over edge being indicated at 3. The blank from which the outer member 2 is formed is shown in full lines at 8 in Fig. 4. After the inner member 1 has been formed, as shown in Figs. 2 and 3, said inner member is placed on the blank 8 so that the heel portions of the inner member 1 and blank 8 coincide with each other. 5 10 This relative position of the inner member and blank 8 is shown in dotted and full lines Fig. 4. The blank 8 is of such a size and shape that when the inner member is thus positioned thereon, the edge portion 9 of the blank 8 will project beyond the inner member. 15 After the inner member and blank are thus positioned, the projecting edge portion 9 of the blank 8 is folded against the inner member 1 into the shape 20 and contour shown in Figs. 6 and 7, that is, the portion or zone of said projecting edge 9 immediately circumjacent the edge of the folded inner member 1 is folded back on itself to present the folded edge 4 of the 25 completed insole, and the extreme peripheral edge of the blank 8 is folded to present the lip 5 which lies against and in contact with the peripheral edge of the inner member 1. In thus folding the projecting portion 9 of the blank 8, the folded inner member 1 of the insole acts as a die or former to assist in giving the proper shape to the folded edge portion of said blank. 30

It will be understood, of course, that if 35 necessary the blanks may be properly tempered before the folding operation, as is customary where leather or similar sheet material is to be folded. I also wish to state that the folding of the blanks will preferably be accomplished by means of suitable dies which may be heated in the usual manner if necessary to assist in setting the folds. When this is done, both blanks will be subjected to pressure and heat to produce and set the folded portions thereof. The 40 inner and outer members may be secured together in any suitable way. I will, preferably, however, apply a coating of adhesive material to the face of the folded inner member 1 that contacts with the blank 8 and will subject the inner and outer members to pressure either during the folding of the edge portion 9 of the blank 8 or afterward in order to cause the two members 45 to firmly adhere together. When this insole is being sewed into a welt shoe, the infolded edge 3 of the inner member 1 acts as a guide for the inseam stitches, and the inseam stitches which attach the insole to the 50 welt and shoe upper pass through the upturned rib 5 and through the inner member 1 at the line of fold so that the stitches lie under the infolded portion 3. 55 60

One advantage of my improved insole is

that it provides an inseam-receiving rib 65 which furnishes ample strength to hold the inseam stitches, but which can be readily flattened out, thus avoiding the presence of an objectionable rib beneath the inner sole of a shoe which often produces more or less discomfort to the wearer. It will be noted that the strength of the inseam-receiving rib is the combined strength of the portion 5 of the outer member and the infolded portion 3 of the inner member, and 70 even when both of these members are made of thin leather or fabric, the combined strength of both furnishes ample strength to hold the inseam stitches. It will also be noted that the portion 3 of the inner 75 member is folded down against the body thereof so that the upstanding portion of the rib is simply the portion 5 thereof. Inasmuch as the outer member can be made of relatively-thin material, the action of the 80 usual beating-down machine on the lasted shoe will be to fold the lip 5 over outwardly, thus making a relatively-flat rib which will not cause any discomfort to the 85 wearer of the shoe. 90

I claim:

1. The method of making a composite insole comprising an inner and an outer member which consists in folding the edge portion of the blank for the inner member over 95 onto the body thereof, placing said folded blank onto the blank for the outer member with the edge of the latter blank projecting beyond the edge of the folded blank and then folding said projecting portion of said 100 latter blank back onto the body thereof and forming the peripheral edge into a lip.

2. The method of making a composite insole comprising an inner and an outer member which consists in folding the edge portion of a blank for the inner member over onto the body thereof, placing said folded blank onto the blank for the outer member with the edge of said latter blank projecting beyond the edge of the folded blank 110 and then folding back on itself the portion of said projecting edge immediately circumjacent the edge of the folded blank and forming the peripheral portion of said projecting edge portion into a lip. 115

3. The method of making a composite insole comprising an inner and an outer member which consists in folding the edge portion of a blank over onto the body thereof, attaching said folded blank to another blank 120 with the edges of said other blank projecting beyond the edge of the folded blank and then folding the portion of said projecting edge immediately circumjacent the edge of the folded blank back on itself and into contact with the periphery of said folded blank 125 and forming the peripheral edge of said projecting portion into a lip.

4. A composite insole comprising an inner member having the edge portion thereof folded back onto the body thereof and an outer member having the edge thereof projecting beyond the periphery of the inner member and formed by folding back on itself the portion of the outer member di-

rectly circumjacent the inner member, the peripheral edge of said outer member being free and forming a lip. 10

In testimony whereof, I have signed my name to this specification.

AUGUST R. SCHOENKY.
